GARBAGE INCINERATOR SYSTEM

Maurice Blumenthal, Brooklyn, and Louis Casper,
Richmond Hill, N. Y.

Application February 9, 1935, Serial No. 5,830

12 Claims. (Cl. 110—8)

This invention relates to systems of garbage and refuse incineration in which operations are conducted on a large scale, as in the case of municipal plants for the disposal of such material.

5 The present application is a continuation in part of our prior copending application Serial No. 633,258 filed September 15, 1932.

An object of the invention is the provision of a novel method of incineration, wherein the material is ignited and burned electrically, thus 10 eliminating grate burners and the necessity of using supplemental fuel.

Another object is the provision of a novel method and means for deodorizing and purifying 15 the gaseous products of combustion from a battery of incinerator chambers in a disposal system or plant.

Another object is the provision of a novel method of breaking slag in incinerator chambers, by the application of fluid under pressure.

20 A further object is the provision of an incineration system electrically operated and controlled and including means for translating the heat energy of the gaseous products of combustion into electrical energy for the supply of power and current to the system.

Other objects will be apparent to those skilled in the art.

In the accompanying drawings:

30 Figure 1 is substantially a vertical section taken through an incinerator plant as equipped with the system of this invention.

Figure 2 is substantially a horizontal section taken on the line 2—2 of Figure 1.

35 Figure 3 is substantially a vertical section taken on the line 3—3 of Figure 2, and with one of the incinerator chambers shown in elevation.

Figure 4 is an enlarged view of substantially a vertical section through an incinerator chamber as shown in Figure 1.

40 Figure 5 is substantially a vertical section taken on the line 5—5 of Figure 4.

Figure 6 is a horizontal section through an incinerator chamber and illustrating the details of 45 mounting the electrical incinerator elements.

Figure 6a is a section similar to Figure 6 but illustrating a modified structure.

The system comprises a battery of incinerator chambers 1, 8, 9 and 10 arranged side by side 50 transversely across a shed 11 with the chambers being disposed beneath a floor 12 at some distance inwardly from the entrance 13 through which garbage and refuse trucks, as indicated by the dotted line showing 14 of Figure 1, are adapted to pass over the floor 12 to discharge

their load into the top of the incinerator chambers.

A ventilating hood 15 is provided over the battery of incinerator chambers and behind these chambers is located a boiler 16 within which the heat from the gaseous products of combustion of the incinerator chambers is utilized to generate steam that is led through a steam conduit 17 to a power plant 18 including electrical generator means which provides current for operating the 10 various electric motors of the system and for furnishing the current necessary to operate the electrical incinerators.

Each of the incinerator chambers comprises a vertical shaft 19 of refractory material and of 15 heat insulating characteristic, that is substantially rectangular in cross section and open at its top and bottom. Adjacent the top each incinerator chamber is provided in its rear wall with a flue through which the gaseous products of 20 combustion are passed from the chamber. The chambers 1, 8, 9 and 10 are respectively provided with the flues 20, 21, 22 and 23 which extend rearwardly of the incinerators in communication with a gas mixing and purification chamber 24 25 located immediately beneath the boiler 16 and which has a single outlet 25 through which the hot gases from the gas purification chamber are passed to the boiler. As best shown in Figure 2, the flues from the respective incinerator chambers enter the gas mixing and purification chamber 24 at points spaced apart serially along the 30 front wall of the chamber. This chamber 24 is divided into separate front and rear compartments by a longitudinal baffle plate 26 which 35 terminates at each end in spaced relation inwardly from the side walls of the chamber. At each end of the baffle 26 the passage thus provided between the baffle end and the adjacent side wall of the chamber is controlled by a 40 damper, the two dampers being shown as at 27 and 28 in Figure 2. These dampers are selectively operable by known means, not shown, whereby to close the passageway at either end of the baffle 26 for selective directional flow of the gases 45 from the incinerator chambers along the forward side of the baffle. The walls of the gas purification chamber 24 are provided with exposed electrical heaters 29 such as imbedded electrical resistors that are made incandescent by electrical 50 current supplied thereto by appropriate circuit connections, not shown. Electrical arc means such as shown at 30 and 31 in Figure 2 are also employed in any desired number and in any desired disposition within the gas mixing and

purification chamber 24. These arcs either with or without the cooperation of the electrical heaters 29, or the heaters 29 themselves with or without the cooperation of the arcs are arranged and adapted to burn and purify the gases passing therethrough from the battery of incinerator chambers.

Each of the incinerator chamber flues 20, 21, 22 and 23 is provided with a vertically slidable 10 damper or valve 32 operable by an electric motor 33 through a suitable operating connection, such as a conventional rack and gear as shown. Each furnace chamber is observed through suitable 15 visual openings common to furnaces for degree of smoke which is also indicative of accumulation of gases in said furnace chambers. When such accumulations reach their maximum the motor 33 is operated being remote controlled as at the panel 74 which causes the damper 32 to open 20 thereby releasing said smoke and gases into intermediate chamber 24.

Each incinerator chamber has its wall 19 lined with a plurality of superimposed sections 34 of refractory material and which are provided with imbedded ribbons 35 of electrical resistor material which become incandescent when current is applied thereto. These electrical resistors 35 constitute electrical igniting and incinerating means on the interior walls of the respective 30 incinerator chambers. These elements 35 are exposed to the interiors of the chambers for active and direct contact with a body of garbage or other refuse material 36 with which the chamber may be charged, as shown in Figure 1. In 35 place of the elements 35, or in conjunction therewith, conventional electrical arcs are employed extending through the walls of the chambers for igniting and burning the material therein. As shown in Figure 6, the respective electrical 40 resistors elements 35 are electrically connected by leads extending through the walls of the chamber to bus bars 37 suitably mounted on the outer face of the incinerator chambers and appropriately connected in an electrical circuit, not 45 shown, by which the necessary energizing current is supplied to the elements 35.

Each of the incinerator chambers is constricted at its bottom portion where the walls converge toward the bottom outlet ring 38. Immediately 50 above the outlet ring 38 the constricted wall portions of the chambers are provided with a series of radial ports 39 in communication with a manifold 40 surrounding the bottom of the chamber. The bottom of the manifold is closed by detachable closure means 41, here shown as a plate, that 55 may be removed for cleaning through a discharge passage 42 opening vertically to the ash pit 43 beneath each incinerator chamber.

As shown best in Figure 1, an air inlet conduit 60 44 provided with a pump 45 communicates with the manifold 40 above the plate 41 for the supply of air under pressure to the manifold for injection through the ports 39 upwardly through the body of the material disposed within the 65 chamber. Also communicating with the manifold 40 above its closure plate is a steam pipe 46 controlled by a valve 47 through which dry steam from a super-heater 48 within the boiler 16 may be supplied to the manifold for injection into the 70 body of the material within the chamber.

Referring particularly to Figures 4 and 5 it will be seen that the bottom of each incinerator chamber is adapted to be closed by a power driven movable closure element operable horizontally beneath the incinerator chamber and

which in this embodiment comprises a flat plate 49 carried by a wheeled frame 50 horizontally movable along a track-way 51 through an appropriate known connection with a screw-threaded shaft 52 driven by suitable gearing within a 5 gear housing 53 from a drive shaft 54 operatively connected with the armature shaft of an electric motor 55. Depending upon the direction of rotation of the driven shaft 52 the bottom closure plate 49 is moved across the lower end of the 10 incinerator chamber to open or close the bottom. When the closure plate 49 has been moved to open position after incineration, the incinerated contents of the chamber fall through the end ring 38 into portable receptacle means 56, here 15 shown as dump-cars operable along track-way means 57 disposed within the ash pit.

The open top of each incinerator chamber is vertically aligned with a material hopper 58 located in the flooring 12 through which material 20 is fed from the vehicles 14. These hoppers are adapted to be closed by pairs of hinged covers 59. Beneath the hoppers 58 the open top of each incinerator chamber above its top ring 60 is adapted to be closed by a horizontally slidible 25 closure member that is power operated and which in general construction and mode of operation is similar to the bottom closure member. In the embodiment as illustrated herein the top closure member comprises a flat plate 61 carried by a 30 wheeled frame 62 operable over a track-way 63 through the medium of an appropriate known connection with a screw-threaded shaft 64 that is driven through a gearing connection within the gear housing 65 from a drive shaft 66 operatively coupled to the armature shaft of an electric motor 67. Depending upon the direction of rotation of the driven shaft 64 the top closure plate 61 will be moved across the top of the incinerator chamber either to open the same or to 40 effect a sealed closure after a load of material 36 has been deposited in the chamber through the hopper 58. In order to drain off liquid accumulating on the bottom after a charge of material has been dumped in an incinerator chamber, 45 each chamber has its bottom ring 38 provided with a liquid discharge drain conduit 68 communicating with a drain 69 through which the liquid product may be discharged or carried to appropriate apparatus for by-product 50 treatment.

Referring to Figure 6 there are shown electric arc electrodes 70 and 71 that are projected into said incinerator chamber for igniting and incinerating the chamber contents and it is to be 55 understood that any desired number and desired arrangement of these arcs may be employed as may be found desirable. There is also shown electrical resistor elements 35 within the liner sections 34, these elements as shown at 35' in Figure 6a and are extended transversely across the interior of the chamber for direct physical contact with the material disposed therein. The electrode structures as above set forth may be used in combination or applied separately. The usage of said electrodes may be varied in accordance with the kinds and quantity of waste materials introduced into said chamber.

In the outlet flue of each incinerator chamber is mounted a heat responsive element 72, preferably of the thermo couple type, which extends through the flue wall for connection in an electrical circuit, not shown, by which the temperature of the gases in the flue is electrically registered by appropriate instruments 73 mounted

upon the control panel 74 with which the system is provided at a point remote from the incinerator chamber. In connection with this control panel 74, it is to be noted that the entire complement 5 of electrical apparatus in the system is controlled by appropriate instruments mounted upon this panel. The operating circuit and connections for such apparatus are well known and the specific wiring details have been omitted from the drawings 10 in order to eliminate confusion of detail. All of the electrical motors as employed in the system are of the reversible field type whereby appropriate directional movement may be imparted to the apparatus which each motor serves.

15 In the operation of the system the incinerator chambers are charged in the manner described, their bottoms being closed so that the load of material 36 is deposited and rests upon the bottom closure plate 49. After charging, the top of 20 each chamber is closed and sealed by its top closure element 61 and the electrical igniting and incinerating means is energized to effect the incandescence of the chamber charge. It is obvious that when the garbage mass has been brought up 25 to said state of incandescence the combustible units contained in said mass will cause the further burning of the incandescent mass without further need of the energized electrodes contained in said chambers and at this stage of incineration the 30 electric power current may be switched off said electrodes thereby effecting an economy in electric power consumption. Liquid collecting at the bottom of the chamber drains off through the discharge conduit 68 and with the gas flue damper 35 appropriately positioned, the burning of material within the chamber is continued at a desired temperature, the temperature being indicated upon the control panel through the heat responsive means 72 as described.

In the illustration of Figure 2 the incinerators 7 and 10 are shown as in operation while the incinerators 8 and 9 are in open position ready to receive a charge. All of the incinerators may be operated in unison or any number as desired, and refuse or garbage material of different characteristics may be burned in different incinerators. A feature of the invention resides in the fact that in the operation of the system the incinerators are operated at different temperatures. Certain refuse material may be completely incinerated at a lower operating temperature than the material charged within the remaining incinerator chambers. It is intended that at least one incinerator of the battery shall be operated at a temperature considerably elevated with respect to the temperature existing in the remaining incinerator chambers. With the battery in operation under this arrangement the gaseous products of combustion are discharged into the purification chamber 24 at points spaced apart along the forward wall thereof in advance of the baffle 26. Assuming, in the showing of Figure 2, that the incinerator 7 is operating at a very high temperature while the incinerator 10 is operating at a lower temperature, the damper 27 is opened while the damper 28 is closed so that the gases passing from incinerator 10 are forced to travel longitudinally along the entire length of the baffle 26 to meet and mix with the high temperature gases coming from incinerator 7. By this means the lower temperature gases are mixed with the highly heated gas from incinerator 7 and are burned and purified by this mixing. The gases as mixed pass through the damper 27 behind the baffle 26 and through the single outlet leading to

the boiler 16. If the higher temperature incinerator should happen to be incinerator 10, the damper 28 is opened while the damper 27 is closed so that the gases from incinerator 7 and the intermediate incinerators of the battery are caused 5 to travel along the front face of baffle 26 to mix with the higher temperature gases at the other end before passing to discharge. This arrangement provides a selective control whereby the gases from the various incinerators of a battery 10 are controlled in their flow in order to provide for a complete mixing and combustion thereof before being discharged. This mixing is materially assisted by the presence of the electrical burner 29 within the chamber 24 acting individually or in conjunction with the arcs 30 and 31. Due to this heating the gases are super-heated within the chamber 24 so that not only are they purified and deodorized but they are delivered to the boiler 16 in a highly heated condition. 20

The material in the various incinerator chambers being in direct physical contact with the exposed electrical igniting and heating means 35, is rapidly elevated to a high temperature whereby incineration is effected. Where conditions require it, the pump 45 for any particular incinerator chamber is operated to discharge air under pressure into the incinerator chamber manifold 40 for ejection through the port 39 upwardly at an angle through the material within the chamber. 30 This provides a forced draft and the air assists in the complete combustion of the material. Instead of using air from the conduit 44, super-heated dry steam from the steam pipe 46 for any particular incinerator chamber may be injected through the manifold and the incinerator chamber port 39 under such pressure as to agitate the chamber contents and break up the formation of slag occurring at the bottom of the incinerator chamber. This is a distinctive feature over 35 prior practice in slag breaking where mechanical means are employed to slice and break up the slag as it is formed. In the practice of this invention the superheated steam is employed as a fluid pressure medium injected directly into the mass 40 of material whereby to break up slag and prevent its formation. Not only is this extremely effective in this matter, but under conditions of extremely high temperature within the incinerator chamber the steam may be disintegrated to its 50 component elements of hydrogen and oxygen, both of which are of material assistance in complete combustion of the contents, as these elements are additional fuel that is injected directly into the body of the chamber contents. 55

The present invention also contemplates the automatic operation and control of the respective dampers for the incinerator chambers under the influence of the heat responsive means 72 associated with each chamber. The operating circuit 60 connections for accomplishing this are not shown for the reason that such circuits are well known and their inclusion is thought unnecessary other than by reference.

The present disclosure constitutes an operative embodiment of the principles of our invention. It is to be understood that the structural details may be varied as desired within limits not inconsistent with the scope of the invention as claimed. 65

We claim:

1. The method of incinerating garbage and refuse material, which consists in placing the material in a chamber, producing therein an incinerating temperature, and agitating the mate- 70 75

- rial by injecting thereinto under pressure a non-inflammable fluid capable of disintegrating at high temperatures into gaseous fuel elements that promote combustion.
- 5 2. The method of incinerating garbage and refuse material which consists in heating and igniting such material in a chamber, and agitating the material with dry steam while it is being burned.
- 10 3. The method of incinerating garbage and refuse material which consists in heating and igniting such material, introducing dry steam into the material being burned, and producing a temperature therein sufficient to disintegrate the 15 steam into its component elements.
- 15 4. An incinerator comprising a chamber having walls of refractory material, electrical means in the walls for direct incineration of the chamber contents, a steam pipe in communication with the chamber interior, and means for supplying dry steam therethrough to agitate the chamber 20 contents.
- 25 5. An incinerator comprising a refractory wall chamber having a top material inlet and a bottom outlet, exposed electrical heater elements in the chamber walls, power driven sealing closure means at said inlet and outlet, and means for injecting a fluid under pressure at the chamber bottom to break slag and agitate the chamber 25 contents.
- 30 6. A garbage and refuse incinerator comprising a vertical chamber open at its top to receive material to be burned and having a bottom open to discharge material therefrom, a top closure therefor, a bottom closure therefor and providing a bottom for the chamber when closed, a sludge drain leading from said chamber at its lowest portion, the walls of said chamber having a series 35 of ports immediately above said drain, a manifold communicating with said ports, means for supplying a fluid under pressure to said manifold, a damper controlled gas flue leading from the chamber, electrical heating and igniting elements in the chamber walls and exposed to its interior, 40 and means for supplying operating current to said electrical elements.
- 45 7. A garbage and refuse incinerator comprising a vertical chamber having a top material delivery inlet, closure means therefor, said chamber having a bottom material discharge outlet, a gate movable across said outlet to close the same and provide a bottom for the chamber, a lining of refractory material on the walls of said chamber, electrical resistor elements carried by the lining 50 and exposed for physical contact with material when in the chamber, fluid injector means in the bottom of said chamber, and means for supplying current to said resistor elements to heat and ignite material when in the chamber.
- 55 8. In a system for incinerating garbage or like wastes said system having a furnace chamber, said chamber having electrode means therein to incinerate waste materials contained in said fur- 60
- nace chamber, said electrodes affixed in said furnace chamber and projecting substantially to the central portion of the mass in the chamber, whereby initially the maximum temperature rise of said waste material mass during the process of incineration of said materials is approximately at the central or heart portions of said mass, thereby effecting a sloping downward gradient of temperature of said mass of waste materials toward the refractory walls of said furnace, oxidizing means applied to said chamber to hasten the incineration of said garbage mass, and remote controlled means provided for the escape of smoke and gases from said chamber as set forth.
9. In a system for the incineration of garbage or like waste materials, a garbage receiving chamber, exposed electrode means positioned substantially centrally of the chamber space with respect to the refractory walls of said chamber, means for electrically energizing said electrodes to heat and cause the incandescence of garbage or waste mass deposited in said chamber, said central location of said electrodes to cause a maximum temperature in said chamber to occur in the area surrounding said electrodes, and minimum temperatures to occur at the refractory walls of said chamber for the purpose as set forth.
- 10 10. The system of claim 9 in combination with remote controlled means for carrying off gases emanating from said chamber, and means for superheating said gases after passing from said chamber whereby to cause a precipitation of smoke and objectionable materials intermixed with said gases that are permitted to escape from said chamber.
- 15 11. In a system for incinerating garbage or the like wastes having a furnace chamber, said chamber having electrode means therein to incinerate waste materials contained in said chamber, said electrodes affixed in said chamber and projecting substantially to the central portion of the mass in the chamber, whereby initially the maximum temperature rise of said waste material mass during the process of incineration of said materials is approximately at the central or heart portions of said mass thereby effecting a sloping downward gradient of temperature of said mass of waste materials toward the refractory walls of said chamber, and oxidizing means applied to said chamber to hasten the incineration of said garbage mass aforesaid.
- 20 12. The method of incinerating a mass of garbage and refuse material, which consists in producing initially a state of incandescence at the central interior of the mass whereby to ignite the material thereat, discontinuing the production of incandescence following ignition of the material, and supplying an oxidizing medium throughout the mass to promote its complete combustion.

MAURICE BLUMENTHAL,
LOUIS CASPER.
